UNITED STATES PATENT OFFICE.

SIDNEY GEORGE BROWN, OF NORTH ACTON, ENGLAND.

ELECTRICAL TRANSMISSION OR REPRODUCTION OF SOUND.

Application filed May 29, 1922. Serial No. 564,386.

To all whom it may concern:

Be it known that I, SIDNEY GEORGE BROWN, a subject of the King of Great Britain, residing at Victoria Road, Willesden 5 Lane, North Acton, in the county of Middlesex, England, have invented certain new and useful Improvements in the Electrical Transmission or Reproduction of Sound, of which the following is a specification.

10 This invention relates to the electrical transmission or reproduction of sound for telephonic purposes or for use with a gramophone, phonograph or like sound recording instrument. One object of the invention is 15 to obtain a reproduction of the sound in a loud tone which can be heard over a considerable distance and is free from the disturbances usually accompanying sound reproduction.

20 A further object is to conduct away rapidly the heat generated in a microphone utilizing substantial currents so as to prevent disturbances due to an excessive rise in temperature. A still further object is to provide in a microphone built up of massive parts for easy and efficient filling of the microphone chambers with the microphone granules.

In order that the said invention may be 30 clearly understood and readily carried into effect, the same will now be described more fully with reference to the accompanying drawings, in which:-

Figure 1 is a section of a microphone device embodying this invention.

Figure 2 is a part front elevation and Figure 3 a back view of the same device.

Figure 4 is a detail view to a larger scale showing the connection between a pair of 40 microphone plates.

Figure 5 is a diagram of a transformer circuit embodying one feature of this invention, and

Figures 6, 7 and 8 are diagrammatic views 45 showing an arrangement of microphones as fitted to a gramophone.

The left upper corner of Figure 1 between the lines $x-x$ is a section on the line $y-y$ of Figure 3, while the remainder of Figure 1 50 is a central section on the line $z-z$, Figure 2. The lower half of Figure 2 is a front elevation of the device while the upper half shows the front part removed to expose the discs of which the casing is built.

55 Referring to the construction of the microphone shown in Figures 1 to 4, the body

of the microphone is built up in the form of a substantial metal casing made in a series of disc-like members A each placed between a pair of discs or plates B, the discs A having a central hole α forming a cell receiving the central plate or diaphragm C of the differential microphone and the microphone granules between which the plate C lies. The discs A and B are insulated from each other by the thin insulating layers D. The end walls of the diaphragm chamber or cell α are formed by the discs B, the opposite faces of which are recessed to receive the carbon plates b which constitute the actual 60 microphone walls. The central plates C, two of which are shown but which may be of any convenient number, are connected rigidly together by the rod or stem e which, as shown in Figure 4, passes through the 65 distance sleeve e' , which may be of aluminum, and projects at one side for attachment to the light conical receiver diaphragm E, if such diaphragm is employed, or to any other oscillating member, such as a member 70 mechanically connected to a gramophone needle. The plates C need not be mounted one behind the other on a single rod, but may be in parallel on branching rods so long as the connection between them ensures vibration in phase. The plates C are secured to the stem by the small nuts e^2 , which may be 75 soldered in position after adjustment.

It will be seen that the microphone plates C vibrate in the same phase and any increase 80 of pressure on the granules at one side of a plate is associated with a corresponding decrease of pressure on the granules at the other side, so that if the microphone is connected up in a differential circuit, as for 85 example the circuit shown in Figure 5, current variations of considerable strength will be set up.

The discs A and B are clamped together by the screws F which extend completely 90 through the pile and are enclosed in insulating sheaths f . The ring or frame G carrying the diaphragm E is also secured to the casing by these screws. The light conical diaphragm is mounted in the ring G by the 95 light flexible carrying ring e secured by the clamping ring g .

On the back plate B is mounted an insulating block H carrying the four screw terminals h on the four metal plates h' which are 100 connected to the respective four discs B by screws h^2 , one of which is shown in Figure 1,

passing through the insulating sheath h^3 and screwing into the second disc B. The central plates C are connected up to a separate lead so that the microphone circuit is completed through the plates C, the carbon granules in the cells a, the end plates b, discs B, terminals h and the external leads and battery. The plates C may be supported in the cells by suitable soft insulating material lining the cell wall and permitting free to and fro movement while giving support. The two halves of the cells a are divided by the plate C and the granules in the two halves kept separate.

To fill the cells a the discs A are made with the deep notches or recesses a' at the upper side and small holes a² closed by plates a³ are provided at the bottom of the recesses a', leading into the cells a, as shown clearly in Figure 2. The plates a³ are removed to open the holes a² and give access to the cells and when these are properly filled a packing of cotton wool or like material may be pushed into the holes a² before replacing the plates a³.

The microphone device shown is one particularly adapted for use with substantial current for loud speaking reproduction for gramophones or other instruments. The overheating of the microphone has hitherto caused difficulties and has given rise to faulty and irregular transmission. In the present construction the mass of metal in direct contact with the microphones enables the heat to be conducted away rapidly and therefore avoids risk of overheating.

In Figure 5 a telephonic circuit is shown which illustrates a special use of the differential microphones. The centre plates C are connected to one pole of a battery J while all the side plates are connected up in parallel to the other pole of the battery through the primaries k of the transformer K, the secondary coils k' of the transformer being connected in series in the telephone receiver circuit L, a receiver (or if preferred a telephone relay) being indicated at l. More than one receiver or relay l may be included in the circuit. For loud reproduction of the sound loud speaking telephones may be employed, with megaphone trumpets. The secondary coils k' are as shown connected up alternately in opposition so as to compensate for any current changes which may be in the same direction in the primary coils, while the current changes due to the differential microphones are necessarily in opposite directions in the two coils connected to the opposite plates. Thus no disturbances in the local battery circuit which are not due to the differential action of the microphones themselves would affect the secondary or receiver circuit.

Where two or more microphones are used, as in the diagram, the plates C are connect-

ed together as already described in order to vibrate in phase, but a single microphone may be employed with the transformer coils arranged to compensate each other. The circuit shown is given merely as one example of a compensating transformer and the differential microphone may, for example, be connected at its centre plate to the middle of a split battery to the poles of which the side plates are connected, the primary and secondary coils being so related as to give the required compensation in the secondary circuit.

In Figures 6, 7 and 8 an arrangement is illustrated diagrammatically by which a powerful reproduction is obtained at any distance, preferably by a set of loud speaking telephones with trumpets arranged at suitable positions in a hall or room. The gramophone is provided with a corresponding set of differential microphones M each of which may be of the double or multiple differential microphone type already described with reference to Figures 1 to 4. These are placed across the end of the sound horn N on the end plate n which may close the end of the sound horn N completely or may have sound apertures (see Figure 8) n' so that the gramophone can also be heard directly in the usual manner.

The horn N is arranged in any convenient manner in the casing, preferably terminating at the front as in the box horns commonly employed, passing from the tone arm O carrying the goose neck o and sound box o' with needle o² traversing the disc P. The sound produced in the sound box o' is transmitted through the horn N to all the microphones M, which are vibrated in phase with each other. They may be connected to a single loud speaking receiver as they vibrate in phase, but usually it is better to employ a corresponding number of receivers and horns or trumpets to distribute the sound more evenly in a large room. The connection between the microphones and receivers may be through a transformer arranged to compensate for external disturbances in the manner already described with reference to Figure 5.

What I claim and desire to secure by Letters Patent of the United States is:—

1. A microphone comprising in combination, a plurality of substantial metal plates secured face to face, insulating material between said plates separating them from each other, one of said plates intermediate between the others having an aperture therein forming a microphone cell, a microphone plate supported in an insulated manner within said aperture, an external vibratory member, and means for connecting said vibratory member to said microphone plate, as set forth.

2. A microphone comprising in combina-

- tion, a plurality of substantial metal plates secured face to face, insulating material between said plates separating them from each other, certain of said plates intermediate between the others having apertures therein forming microphone cells, a microphone plate supported in an insulated manner within each of said apertures, an external vibratory member common to all said microphone plates, and means connecting said vibratory member to said microphone plates in such a manner that they vibrate in unison, as set forth.
3. A microphone comprising in combination, a plurality of substantial metal plates secured face to face, insulating material between said plates separating them from each other, one of said plates intermediate between the others having an aperture therein forming a microphone cell, a microphone plate supported in an insulated manner within said aperture, carbon discs mounted in recesses in the plates adjacent said intermediate plate forming the microphone walls, an external vibratory member, and means for connecting said vibratory member to said microphone plate, as set forth.
4. A microphone comprising in combination, a plurality of pairs of substantial metal plates having recesses therein, insulating material between each pair of plates, a metal plate of larger dimensions than said recessed plates provided with an aperture and inserted between the two plates of each pair, insulating material separating said larger plates from said other plates, a microphone plate supported in an insulated manner within each of said apertures, an external vibratory member common to all said microphone plates, and means connecting said vibratory members to said microphone plates in such a manner that they vibrate in unison, as set forth.
5. A microphone comprising a massive metal casing built up of a series of substantial metal plates secured face to face, a central aperture in an interior plate, forming a microphone cell, a microphone plate supported in an insulated manner within the said cell and between the adjacent metal plates on each side, a deep channel in the said interior plate opening to the cell whereby access is obtained to the cell for filling purposes and means for closing the opening to the cell when the latter is filled.
6. A microphone comprising a massive metal casing built up of a series of substantial metal plates secured face to face, a central aperture in an interior plate, forming a microphone cell, a microphone plate supported in an insulated manner within the said cell and between the adjacent metal plates on each side, a deep channel in the said interior plate opening to the cell aperture, a passage leading from the channel into the cell aperture and a small covering plate for the said passage.

SIDNEY GEORGE BROWN.
